(Cl. D33—2)

To all whom it may concern:

Be it known that I, Milton B. Smith, a citizen of the United States and a resident of Huntington, Huntington County, Indiana, have invented a new, original, and ornamental Design for a Phonograph Record Holder Frame, of which the following is a specification, reference being had to the accompanying drawing, forming a part thereof.

In the drawing:

Figure 1 is a top perspective view of the phonograph record holder frame, showing my new design;

Figure 2 is a top plan view of the phonograph record holder frame; and

Figure 3 is an end elevational view of the phonograph record holder frame.

I claim:

The ornamental design for a phonograph record holder frame, as shown.

MILTON B. SMITH.
